UNITED STATES PATENT OFFICE.

LESTER W. BURTON, OF SYRACUSE, NEW YORK.

DESIGN FOR ADVERTISING-DESKS.

Specification forming part of Design No. 7,170, dated February 17, 1874; application filed January 6, 1874.
[Term of Patent 7 years.]

To all whom it may concern:

Be it known that I, LESTER W. BURTON, of Syracuse, in the county of Onondaga and in the State of New York, have invented a new and original Design for Advertising-Desk; and do hereby declare that the following is a full, clear, and exact description thereof, reference being had to the accompanying drawings, making a part of this specification, in which—

Figure 1 is a front elevation of my improved desk as arranged for use, and Fig. 2 is an end elevation of the same.

Letters of like name and kind refer to like parts in each of the figures.

My invention is an improvement in the style of advertising-desks for use in hotels and other places of resort; and it consists in the improved design, substantially as shown and described.

In the annexed drawings, A represents the table, resting upon and supported by a number of legs, B and B, and having at its upper side two sloping leaves, C and C, which, from points near its transverse center, incline downward and outward, as shown in Fig. 2. The sides of the table A are ornamented by panels a a, while the legs B and B have the form shown, and at their upper ends are provided with a number of ornamental brackets, D and D, which extend between said legs and the lower edge of the side rails of said table, and between said legs and the projecting edges of the leaves C and C. Extending longitudinally

through the center of the upper side of the disk, between the inclined leaves C, is a frame, E, the sides of which slope upward and toward each other, and are provided with a number of sign-panels, F. A similar panel, F', is placed at each end of said frame, and at its upper and lower sides are placed projecting cornices G and H, respectively. Upon the upper plane side of the frame E are several frames or sections, I, the sides of which contain sign-panels K, while at their edges are placed ornamental scrolls L, and each frame is surmounted by a heavy projecting molding, M. Upon the molding or cornice of each frame I is placed an ornamental center-piece, N, sustained at either side by ornamental scroll-work O. At the base of the center section or frame I is placed a card-frame, which frame is divided into a series of vertical compartments, P, the rear walls of which rise in regular order from front to rear, as shown.

Having thus fully set forth the nature and merits of my invention, what I claim as new is—

The design for an advertising-desk, as shown and described.

In testimony that I claim the foregoing I have hereunto set my hand this 26th day of December, 1873.

LESTER W. BURTON.

W. M. DALLMAN,
L. F. ORMSBEE.
